UNITED STATES PATENT OFFICE.

EUGENE O'BRIEN, OF EAU CLAIRE, WISCONSIN.

ATTACHMENT FOR PAPER MACHINES.

Application filed August 8, 1923. Serial No. 656,319.

In packing and marketing fruits of various kinds, it has been customary to wrap each article in paper for the purpose of excluding air, dust and dirt, and preventing the fruits 5 from becoming bruised or marred by rubbing contact in the package. In shipping such fruits by water, particularly a long distance on the ocean, it has been found desirable to impregnate the wrapping paper with 10 a substance, such as oil or wax which will be impervious to moisture. The wrapping paper after passing through the paper machine, has been treated in a separate oil or waxing machine, the process involving a separate and distinct operation from that of passing 15 through the paper machine. This additional operation has added considerably to the labor and expense of treating the wrapping paper and furthermore the oil or waxing machine has added considerably to the 20 cost and upkeep of the plant.

The object of my invention is to save steps and time in the process and eliminate entirely the additional oil dipping machine.

25 A further object is to greatly simplify and reduce the first cost of treating the paper.

The invention consists generally in various constructions and combinations all as hereinafter described and particularly pointed out in the claims.

In the accompanying drawings forming part of this specification,

Figure 1 is a sectional view of a portion of a paper machine illustrating the application of my invention thereto;

Figure 2 is a plan sectional view on the line 2—2 of Figure 1.

In the drawings, 2 represents the frame of the machine of any suitable or preferred construction; 3 is one of the paper rolls over which the web of paper 4 passes. A roll 5 is mounted in the middle portion of the frame above which are rolls 6, 7, 8 and 9, to which the web of paper is delivered in the usual 45 way in machines of this type. As the web passes between the rolls 5 and 6, it is wound on a roll 10 mounted in a reel 11. This reel is also adapted for supporting a roll 10^a, the reel being reversed when one roll is filled to 50 permit the removal of the paper from the filled roll while the paper is being wound on the other roll. All this is well-known construction in a paper machine to which I make no claim of novelty.

55 Instead of having a separate machine for impregnating the paper with oil or wax, I

provide a container 12 having an open top into which the roll 5 projects and wherein it revolves. This container is adapted to contain a supply of oil or, wax or any other 60 suitable paper impregnating material in a liquid state (and may have a heating means not shown). A yoke 13 supports a small roll 14 which bears on the peripheral surface of the roll 5 and is partially submerged in the 65 oil so that as the rolls revolve a thin film of oil will be deposited on the roll 5. Brackets 15 are pivoted at 16 and have arms 17 to which tension springs 18 are connected; said brackets being pivoted on the wall of the container 12 and having sockets wherein threaded rods 19 are adjustable by means of nuts 20. The tension of the springs 18 is sufficient to hold the roll 14 in contact with the roll 5 for the deposit of the oil on the peripheral surface of the roll 5 but whenever desired the nuts 20 may be loosened and the rods 19 withdrawn to pull the oil distributing roll out of the body of oil and out of contact with the roll 5, thus allowing the roll 5 to revolve in 80 the container without having any oil deposited on its peripheral surface.

Upon the opposite side of the roll 5 is a blade 21 having end pivots 22 in the walls of the container and provided with a thin 85 edge 23 that is adapted to bear on the surface of the roll 5 and spread the film of oil thereon. Springs 24 are connected with the blade 21 and operate to hold the edge 23 in contact with the surface of the roll with a 90 yielding pressure. This pressure may be varied so that the coating or film of oil on the roll may be spread out very thin so that only a small quantity is allowed to contact with the paper web or the blade may be adjusted so that it will bear lightly on the roll 5 and allow a considerable accumulation of oil thereon and thus the operator of the machine can easily regulate the quantity delivered to the paper web, and the degree that 95 the web is impregnated with the oil or wax.

For the purpose of regulating the pressure of the blade on the roll, I prefer to provide an arm 25 thereon supporting a weight 26 which is movable back and forth on the arm 100 for the purpose of increasing or decreasing the pressure of the blade on the roll and the depth of the film or peripheral coating of oil thereon. It will be noted that this attachment can be easily and quickly applied to a 105 standard paper machine without any re-adjustments or alterations in the machine; that

the expense of construction of the attachment is comparatively small, involving only the container and the distributing roll and scraper blade, thus eliminating the expense of a 5 separate dipping machine and saving the space which would be required in a paper mill for such a machine.

I claim as my invention:

1. In a paper machine, a receptacle adapted to contain a supply of paper impregnating material in liquid form, a distributing roll partially immersed in the liquid in said container, a series of paper machine rolls arranged one above the other, the lower roll 10 of the series being positioned to contact with said distributing roll to receive therefrom a coating of the liquid in said container, the web of paper passing around the upper rolls of the series and contacting with the lower 15 roll of the series to be impregnated with the coating thereon for the purpose specified, and means bearing on the peripheral surface of said lower roll of the series for evenly spreading the coating in a film of suitable 20 thickness thereon.
2. In a paper machine, a container for liquid paper impregnating material, feed rolls above the liquid level in the container, and means separately adjustable respectively for 25 applying the liquid to the entire surface of one unimmersed feed roll, and for spreading the material in a thin filament entirely across said roll, to be carried to the paper for adsorption thereby.
3. A process for impregnating paper with oil which consists in drying the paper, and

then afterwards and while dry applying the oil to the paper.

4. A process for impregnating paper with oil which consists in drying the paper by heat 40 and then afterwards and while dry applying the oil to the paper.

5. In combination with a drying device of a paper machine, an oil receptacle adjacent the drying device and means to feed the paper 45 from the drying device, toward the oil receptacle, and means associated with the oil receptacle for causing the oil to be evenly applied to the paper.

6. In combination with the drying roll of 50 a paper machine, an oil receptacle immediately adjacent said roll, a roll arranged to receive oil from the receptacle, and also arranged so that the paper is held against it after leaving the heating roll, and while the 55 paper is dry, and means for regulating the depth of the liquid oil film upon the roll before the paper comes in contact with said film.

7. In combination with the drying roll of 60 a paper machine of an oil receptacle, a roll arranged to receive oil from the receptacle, and also arranged so that the paper is held against it after leaving the heating roll, and means for regulating the depth of the liquid oil film upon the roll before the paper comes in contact with said film, said means comprising a wiper element yieldably engaging the roll throughout its length.

In witness whereof, I have hereunto set my 70 hand this 28th day of July, 1923.

EUGENE O'BRIEN.
